ATTORNEY

UNITED STATES PATENT OFFICE.

CHARLES T. OSBORNE, OF ST. LOUIS, MISSOURI.

EXPLOSION-TURBINE.

1,306,388.

Specification of Letters Patent. Patented June 10, 1919.

Application filed November 23, 1916. Serial No. 132,964.

To all whom it may concern:

Be it known that I, CHARLES T. OSBORNE, a citizen of the United States of America, residing at the city of St. Louis, State of 5 Missouri, United States of America, have invented, a certain new and useful Explosion-Turbine, of which the following is such a full, clear, and exact description as will enable any one skilled in the art to which it 10 appertains to make and use the same, reference being had to the accompanying drawings, forming part of this specification.

My invention relates to a turbine motor operated by explosive fluid, and its objects 15 are to produce a motor of this type, which is light and efficient and which has no reciprocating parts.

In the preferred form of my invention I employ a revolving member having combustion 20 chambers communicating with the supply of fuel through openings in a throttle plate or disk against which the revolving member bears and which serves as a closure for the single opening of each combustion 25 chamber. The gas produced by the explosion of fuel in the combustion chambers is discharged into a turbine of ordinary construction, provided with the usual movable and stationary vanes. The revolving portion 30 of the turbine is keyed to the same shaft as the revolving member carrying the combustion chambers.

In the accompanying drawings, which illustrate one embodiment of my invention, 35 Figure 1 is a longitudinal section; Fig. 2 is a top elevation; Fig. 3 is an end elevation; and Fig. 4 is a cross sectional view taken on the line $a-a'$ of Fig. 1.

1 represents the casing of the turbine, 40 which is provided with the usual stationary vanes 2. The rotor of the turbine is provided with the usual vanes or buckets 3, and is connected to a shaft 4. One end of the turbine case is closed by a stationary member 5. In the form shown this member 5 is provided with two fuel reservoirs 6, supplied from a fuel pump 7, and with two vacuum chambers 8 connected to a vacuum pump 9. The fuel pump or compressor 7 45 and the vacuum pump 9 are driven from the shaft 4 through any suitable connections. The stationary member 5 is also provided with ports 10, 11 and with oblique discharge passages 12 and 13 indicated in Fig. 4 and 50 by dotted lines in Fig. 1.

A disk or throttle plate 14 bears against one side of the stationary member 5, and is provided with openings that may be caused to register with ports 10, 11. This throttling plate is also provided with elongated openings 15, 16, registering with the passages 12 and 13 of the member 5. The throttle plate can be shifted circumferentially by a worm and gear 22. A revolving member 17 is keyed to the shaft 4 and bears upon the 60 throttling plate 14. This revolving member is provided with a plurality of combustion chambers 18 and spark plugs 19. Spark plugs 20 are positioned to ignite in the turbine such gases as were unburned when discharged from the combustion chambers 18. 65

For cooling purposes the revolving member 17 may be provided with a plurality of fan blades 21 positioned at an angle to the direction of rotation, and vanes or shields 70 23 may be distributed over the surfaces of the stationary portions of the motor. 75

Suitable clamping means 24 are provided for holding the rotary member 17 in close contact with the throttle plate 14, and, as a 80 further means of producing a gas-tight connection between 14 and 17, either may be provided with two annular tongues coöperating with annular grooves in the other as shown. 85

In the operation of my motor gas and air in proper mixture is forced into the reservoirs 6, and when the end of one of the combustion chambers 18 registers with the port 10 a charge of gas is supplied to the chamber, and further rotation of the revolving member brings it into a position in which the throttle plate seals the opening into the chamber, and the charge is then ignited, thus developing a high pressure in the chamber. 90 Further motion of the revolving member, which is in a clockwise direction, brings the opening of the chamber opposite the slot 15 in the plate 14 and the passages 12 through the stationary member 5, and the gas is thus 95 permitted to discharge against the vanes of the turbine. Further motion of the revolving member brings the combustion chamber into communication with the vacuum pump 8 through the port 11, and the products of 100 combustion still contained in the chamber are thereby withdrawn. The combustion chamber next comes into connection with the second fuel compression chamber 10, 105 which is preferably located 180° from the 110

other fuel chamber, and a cycle, similar to that just described, is repeated, the fuel being received, exploded and the products of combustion discharged into the turbine 5 through openings 13 and undischarged products removed from the chamber through the second vacuum port 11. In the form shown six combustion chambers are provided in the revolving member 17, and each 10 chamber discharges gas into the turbine twice in each revolution of the member 17.

It will be understood that modifications in the number of combustion chambers, fuel chambers, vacuum chambers, form of turbine vanes, and in other features of the particular form of device herein described may be made without departing from the spirit of my invention, and I, therefore, do not intend that the scope of the invention be 15 limited otherwise than as required by the appended claims.

Having fully described my invention, what I claim as new and desire to secure by Letters Patent of the United States is:

25 1. In apparatus of the class described, the combination of a turbine, a revolving member with combustion chambers, a stationary member between the turbine and revolving member and provided with passages for the 30 admission of fuel to the revolving member

and for the discharge of gases from the revolving member to the turbine.

2. In an apparatus of the class described, the combination of a turbine, a revolving element carried on the turbine shaft and 35 provided with combustion chambers, fuel igniting means in said chambers and revolving therewith, and a stationary member between the turbine and the revolving member, said stationary member being adapted 40 to form a closure for the combustion chambers and being provided with spaced fuel-supply and gas-discharge ports.

3. In apparatus of the class described, the combination of a revolving element provided 45 with combustion chambers, a turbine operated by gases discharged therefrom, and a plurality of fan blades spaced around the circumference of the revolving element.

4. In apparatus of the class described, the 50 combination of a revolving element provided with combustion chambers, a turbine adjacent thereto and having its casing provided with spaced air controlling vanes, and fan blades on the revolving element for causing 55 air to pass between the vanes on the turbine casing.

In testimony whereof, I have hereunto set my hand and affixed my seal.

CHARLES T. OSBORNE. [L. S.]
